The ornamental design for a telescopic handle, as shown and described.

DESCRIPTION

FIG. 1 is a front view of a telescopic handle according to my new design showing the handle in a first position;

FIG. 2 is a left side view of the telescopic handle of FIG. 1;

FIG. 3 is a right side of the telescopic handle of FIG. 1;

FIG. 4 is a top view of the telescopic handle of FIG. 1

FIG. 5 is a front view of the telescopic handle of FIG. 1 showing the handle in a retracted position relative to a luggage item, illustrated in broken lines, and turned to the right;

FIG. 6 is a front view of the telescopic handle of FIG. 1 showing the handle in an extended position relative to a luggage item, illustrated in broken lines, and turned to the right;

FIG. 7 is a top view of the telescopic handle of FIGS. 5 and 6;

FIG. 8 is a front view of the telescopic handle of FIG. 1 showing the handle in a retracted position relative to a luggage item, illustrated in broken lines, and turned to the left;

FIG. 9 is a front view of the telescopic handle of FIG. 1 showing the handle in an extended position relative to a luggage item, illustrated in broken lines, and turned to the left; and,

FIG. 10 is a top view of the telescopic handle of FIGS. 8 and 9.
